US00D793415S

(12) United States Design Patent (10) Patent No.: US D793,415 S
Kim et al. (45) Date of Patent: * Aug. 1, 2017

(54) DISPLAY SCREEN OR PORTION THEREOF WITH GRAPHICAL USER INTERFACE

(71) Applicant: Samsung Electronics Co., Ltd., Suwon-si, Gyeonggi-do (KR)

(72) Inventors: Hangyul Kim, Seoul (KR); Sungmin Kim, Seoul (KR); Min-Hee Lee, Seoul (KR); Yunjae Lee, Seoul (KR)

(73) Assignee: SAMSUNG ELECTRONICS CO., LTD, Gyeonggi-Do (KR)

() Term: 15 Years

(21) Appl. No.: 29/548,329

(22) Filed: Dec. 11, 2015

(30) Foreign Application Priority Data

Aug. 12, 2015 (KR) 30-2015-0040794

(51) LOC (10) Cl. 14-04

(52) U.S. Cl.

USPC D14/486

CLAIM

We claim, the ornamental design for a display screen or portion thereof with graphical user interface, as shown and described.

DESCRIPTION

The FIGURE is a front view of a display screen or portion thereof with graphical user interface showing our new design.

The outermost broken lines illustrate a display screen or portion thereof and form no part of the claimed design. The remaining broken lines illustrate portions of the graphical user interface and form no part of the claimed design.

1 Claim, 1 Drawing Sheet
